UNITED STATES PATENT OFFICE

ENRICO PIETRO DE ZAN, OF SPEZIA, ITALY

SPRAYING OF LIQUIDS

Application filed March 2, 1927, Serial No. 172,154, and in Italy November 19, 1926.

This invention relates to the spraying of liquids and more particularly liquid fuel and its principal object is an improved sprayer head construction in which the exit opening 5 has no influence on the atomizing function, this hole serving exclusively to direct the liquid, already atomized when it reaches this hole, to wherever it is required.

Another object of the invention is to create an improved sprayer construction which allows the perfect atomizing of the liquid in a cold condition without requiring either a preheating of the liquid or the use of an atomizing fluid such as compressed air, steam 15 or the like.

In applying the invention to a liquid fuel burner the device according to the present invention provides an atomizer head formed of two annular plates fastened together and 20 with a perfect adherence between their contact surfaces. Upon each contact face of the two plates is applied a system of ports, the system of ports in one face being displaced circumferentially with respect to the system 25 of ports in the other face and each system of ports being constituted by a number of ports which extend from the circumference of the plate and two by two of these ports on each face are united towards the inside in one 30 port which terminates tangentially at the periphery of an inner cylindrical cavity of the head, in which cavity are provided two central bosses functioning as valves for the control of the port openings of the two systems 35 of ports and of which bosses one forming an abutment is fitted with the exit opening of the liquid fuel which has to direct the atomized fuel in the furnace.

A further feature of the present invention 40 consists in a regulating device by means of which it is possible to obtain an identical, gradual, simultaneous opening or closure of the ports upon both faces of the plates of the head of the burner.

The accompanying drawings describe and illustrate by way of example one constructional form of the invention.

Figure 1 is a central longitudinal sectional 50 view of the improved liquid fuel burner;

Figure 2 is a side view of a detail of the atomizing head;

Figure 3 is an end view of Figure 2 showing a system of ports in dotted lines are arranged on the contacting face of one plate 55 of the head and another system of ports in chain dotted lines as arranged on the contacting face of the other plate of the head;

Figure 4 is a partial sectional view taken on the line *a*—*a* of Figure 3;

Figure 5 is a sectional view of the atomizer head taken on the line *b*—*b* of Figure 3.

In these figures 1 is a cylindrical casing within which is coaxially arranged a filter 2 which is seated at one end within a circular groove 3 of a threaded plug 4 at one end of the casing and which is detachably held in position at its other end by said plug against a circular flange 5 at the other end of the casing. Passing axially through the casing is a rod 6 which is tightly supported on the plug 4 by means of the stuffing box 7 engaged with the plug by means of the nut 8. The outer end of the rod 6 passes by means of the threaded portion 9 through the yoke 10 fastened upon the nut 8 by means of the screws 11 so that the rotation of the rod causes the axial displacement of the same. The inner end of the rod 6 by means of the threaded shank 12 is connected to the atomizer head. This head 80 consists of an annular member 13 which is internally threaded to engage the threads 12 on the rod 6, and the member 13 is fastened by means of screws 14 to an annular plate 15 so that a good contact will be obtained by the 85 two contacting annular faces. 16 is a closing plate to the inner end of the burner casing, fastened at its edge between the flange 17 and the annular locking disc 18 threaded in the wall of the casing 1; said socket presents a 90 calibrated central abutment 19 fitting in the cavity 20 of the plate 15 and on this pin rotates with a slight friction the atomizer head. 24 is a calibrated boss integral with and of the same diameter as the threaded shank 12 which 95 fits in the cavity 20 of the plate 13. 21 is an outlet port provided on the pin or boss 19 which directs the liquid fuel, atomized before it reaches this port, into the fire box.

The contacting faces of the member 13 and 100

boss 15 each bear a plurality of sets of ports which pass inwardly from the circumference of the plate towards the inner cavity and there are provided exactly three pairs of ports 22, 22' upon the face of the plate member 13 and three pairs of ports 23, 23' upon the face of the plate 15. The two ports of each pair converge upon the face of each plate and intersect to form one port 22" and 10 23" respectively which end within the central cavity 20 of the atomizer head in a tangential direction to the periphery of the cavity.

The relative position of the plates 13 and 15 is so established that the liquid fuel coming from the ports 22, 22' strikes first at a certain angle against the liquid fuel coming from ports 23, 23' and is then sustained by the latter in its rotating motion.

20 From the arrangement in Figure 4 of the drawings it results that the ports 22, 22', 23, 23' so slope towards one another that the fuel which issues from the inner openings 22" of the port 22, 22' takes a direction the plane 25 thereof which is at an angle to the plane of that coming from the openings 23" of the ports 23, 23'.

The amount of movement necessary to open the ports 23" is established by the position 30 of the atomizer head with respect to the abutment 19 on the closing plate 16 and the amount of the opening of the holes 22" from the condition whether the rod 6 is more or less threaded on to the member 13. In the in-

35 operative position the end face of the boss 24 and the end face of the abutment 19 press against each other and the burner is out of operation. The pitch of the threaded shank 12 on one end of the rod 6 is one half the pitch 40 of the threads 9 on the other end of the rod 6 and the head is prevented in its rotation by pins 26 threaded in the casing 1 which terminate with their end faces against the plane surfaces of "flats" 27 provided on the plate 45 13 of the atomizing head.

The screw threads provided on the opposite ends of the rod 6 are relatively different; that is to say, the threads 9 are of a different number per inch, preferably less 50 than those on the shank 12. By such a differential screw arrangement a positive adjusting action is secured upon the atomizer head such that not only is the boss 24 which forms a primary valve moved to and from the abutment 19 but the non-rotary combined member 13 and plate 15 which form 55 a secondary valve are also moved relatively to the said abutment.

Assuming that the threads 9 are eight 60 threads per inch and that the shank 12 has sixteen threads per inch: in rotating the rod 6 for one revolution in the direction to unwind the same, the rod will be displaced from the casing for about 3 mm. and as the head cannot 65 rotate, the same will unwind for a revolution

and become displaced on the rod for a distance of 1.5 mm. with the result that the opening 23" will be opened for 1.5 mm. and also the openings 22" will be simultaneously opened for exactly the same amount.

The liquid fuel admitted to the burner traverses the socket 25 and driven by pump or reaching the burner from an elevated fuel tank flows through the ports 22, 22' in the plate 13 to issue across the openings 22" in the cavity 20. In these ports the liquid currents strike against each other at a certain angle, the impact initiating the splitting up (disintegration) of the fluid; the same effect takes place in the ports 23, 23' of the plate 15 and in all the pairs of ports. In a second place another impact takes place between the streams of fuel which issue from the openings 22" of the plate 13 and the ports 23" of the plate 15, the fuel assuming then a rotary motion. An increased speed of the liquid which is about 3 meters per second, results from the fact that the two combined streams of liquid from the ports 22, 22' and 23, 23' respectively have to pass through the relatively small ports 22" and 23" in a unit of time and hence the atomizing takes place in a perfect manner without requiring the necessity of a small exit opening 21 for which reason it is not requisite that there should be a preheating of the fuel provided that it is in such a condition that it be pumped without difficulty at the desired pressure.

The fuel burner according to the present invention presents also the advantage with 100 respect to the known burners of the kind that its capacity can be regulated within wide limits and this by simply regulating the rod 6 and with this regulation the amount of the openings of the holes 22" and 23".

It is also to be understood that the device 105 may be used for the spraying of any liquids such as oil, crude oil, paint, water and the like.

Having now described my invention, what 110 I claim as new and desire to secure by Letters Patent is:—

1. Improved liquid sprayer comprising in combination a casing having a closed end, means for supplying liquid thereto, a longitudinal shank extending within the casing, a primary valve at one end of the shank, a fixed abutment on the closed end of the casing in line with the primary valve, a secondary annular valve in threaded engagement 115 with the primary valve and in sliding engagement with the abutment, two sets of atomizing ports passing through the wall of the annular valve, one set adapted to be closed by the abutment and the other by the primary 120 valve, means whereby when the longitudinal shank is rotated to open the ports the primary valve recedes from the abutment to form an intermediate atomizing chamber therebetween the open one set of ports and at the 125 130

same time move the annular valve relatively to the abutment and thereby open the second set of ports in the annular valve, the two sets of ports being simultaneously, identically and gradually opened or closed, and an outlet port in the fixed abutment to directionally discharge the atomized liquid.

2. A liquid sprayer as claimed in claim 1, wherein the longitudinal shank, differentially screw threaded at its two ends and adapted to permit proportionate control of the sets of ports and of the capacity of the atomizing chamber respectively, the threading at one end engaging the casing, an annular valve in screw threaded engagement with the threading on the other end of the shank and means for preventing the rotation of the annular valve.

3. A liquid sprayer as claimed in claim 1, wherein the secondary valve comprises a pair of non-rotatory tubular members maintained in face contact, and a plurality of sets of ports in each contacting face, those in one face being circularly displaced relatively to those in the other face and each set of ports comprising a pair of tangentially directed intersecting passages opening on the external periphery of the corresponding tubular member and converging into a single passage opening on to the internal periphery of the tubular member and the passage from one set of ports being opposed to that from the other set of ports, the whole forming a system of atomizing ports and an internal atomizing chamber.

4. Improved liquid sprayer comprising a casing, a closure therefor with discharge orifice therein, a longitudinal shank within said casing, an open ended chamber carried at the end of said shank constituting an atomizing chamber, a fixed abutment engaging the free end and within the chamber, atomizing ports establishing communication between the said chamber and the casing and means whereby when the shank is turned, movement of the shank relative to the fixed abutment will cover or uncover the ports, thereby simultaneously proportionately varying the capacity of the atomizing chamber and the opening or closing of the atomizing ports.

5. Improved liquid sprayer comprising a casing, a closure therefor with discharge orifice therein, a longitudinal shank within said casing, an open ended non-rotating chamber carried at the end of said shank constituting an atomizing chamber, a fixed abutment engaging the free end and within the chamber, atomizing ports establishing communication between the said chamber and the casing and means whereby when the shank is turned, the end of the shank is differentially moved in relation to the movement of the side walls of the chamber, and the upper wall thereof relatively to the fixed abutment, movement of the shank relative to the fixed abutment

covering or uncovering the ports, thereby simultaneously proportionately varying the capacity of the atomizing chamber and the opening or closing of the atomizing ports.

6. Improved liquid sprayer comprising a casing, a closure therefor with discharge orifice therein, a longitudinal shank within said casing, an open ended chamber carried at the end of said shank, a set of atomizing ports formed in the chamber wall adjacent to the said end of the shank, a fixed abutment engaging the free end of and within the chamber, a set of atomizing ports in the chamber wall adjacent to the fixed abutment, and means for causing a differential movement between the end of the shank and the chamber walls whereby the end of the shank will control one set of ports and the moving chamber wall will control the other set of ports.

In testimony whereof I have signed my name to this specification.
